(57) **CLAIM**

The ornamental design for a square neck pillow, as shown and described.

DESCRIPTION

FIG. 1 is a perspective view of the square neck pillow showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating portions of the square neck pillow and form no part of the claimed design.
